DANIEL W. HIGHTOWER, OF BURLINGAME, CALIFORNIA.

GRINDING-MACHINE.

1,183,299.

Specification of Letters Patent. Patented May 16, 1916.

Application filed December 7, 1915. Serial No. 65,496.

To all whom it may concern:

Be it known that I, DANIEL W. HIGHTOWER, a citizen of the United States, residing at Burlingame, in the county of San Mateo and State of California, have invented new and useful Improvements in Grinding-Machines, of which the following is a specification.

This invention relates to a grinding machine.

An object of the present invention is to provide a simple, cheaply manufactured, easily operated grinding machine for grinding puppet valves, and the like, such as are employed in internal combustion engines; and particularly to provide a mechanism whereby an alternate oscillating and rotating movement may be transmitted to the valve or article being ground.

Further objects will hereinafter appear.

The invention consists of the parts and the construction and combination of parts as hereinafter more fully described and claimed, having reference to the accompanying drawings, in which—

Figure 1 is a central vertical section through the grinding machine. Fig. 2 is a plan view of Fig. 1 showing the cover A removed. Fig. 3 is a diagrammatic view showing the position of the cams.

Referring in detail to the drawings, A indicates a suitably shaped casing, in the lower end of which is vertically disposed and journaled a spindle 2. Journaled in the upper end of casing A and horizontally positioned is a drive-shaft 3, upon which is secured a wheel 4, on the outer face of which is formed a plurality of cams 5 of varying lengths. Inclosing the wheel 4 and forming a closure for the casing A is a cover 6, which is provided with a handle 7. Secured on shaft 3, exteriorly of the casing, is a crank arm 8 by which rotary movement is transmitted to shaft 3 and the wheel 4 secured thereon.

Secured upon the upper end of spindle 2 inside of the casing is a horizontally positioned disk 9, on the upper face of which is mounted a plurality of rollers 10; there being in this instance seven in number (see Fig. 2). The rollers 10, secured upon the disk 9, are so positioned that each pin, during the revolution of the disk and spindle, will come into approximate alinement with a central vertical line 10—10 drawn through

the shaft 3. They are also of such height as to be engaged by the cams 5 formed on wheel 4 and will, therefore, during the revolution of the wheel, by means of the crank arm 8, cause an oscillating movement to be transmitted to the spindle 2.

The cam members 5 are preferably of varying lengths, such as shown in Fig. 3, and overlapped, and each cam is positioned on an angle opposite to the preceding one. 65 This is true of all of the cams except the two indicated at 11 and 12, these being provided for the purpose of advancing the spindle one-seventh of a revolution during each revolution of the wheel 4. There are seven cams of varying lengths on the wheel 4 and seven rollers on the disk 9. The spindle will, therefore, be rotated one-seventh of a revolution during one revolution of shaft 3 and will at the same time be oscillated six times 70 between each one-seventh of a revolution of rotary movement.

When the machine is used for grinding puppet valves, it is only necessary to use a tool similar to a screw-driver, or the like, 80 such as shown at 14. The end of the spindle is socket-shaped to receive the tool, as shown and the set-screws 15 secure it therein. The machine is then grasped by the handle 7 and placed directly above the puppet valve 85 in a position where the screw-driver will register with a slot in the head of the valve; such a slot being usually provided in most forms of valves. The crank 8 is then rotated and an oscillating movement is transmitted from the cams 5 and rollers 10 to the spindle. The valve that is being ground will swing back and forth and each cam 5 is of varying length, as shown in Fig. 3, so that no two oscillating movements are alike. 95

As previously described the cams 11 and 12 being similarly positioned provide a means whereby the spindle is rotated one-seventh of a revolution during one revolution of shaft 3. The spindle is, therefore, turned one-seventh of a revolution, then oscillated six times, again turned one-seventh of a revolution and oscillated six times; the same cycle of operation taking place as long as the crank 8 is turned. Any 100 pressure may be brought to bear upon the valve while it is being ground through the handle 7 without fear of cutting grooves in the valve or seat as the variable oscillations transmitted through the cams 5, together 105 110

with the partial intermittent rotation of the spindle, produces an exact and equal grinding of the valve surfaces.

While a plurality of cams 5 have been provided, it is obvious that the same result may be produced by forming a cam groove in the face of the wheel.

The machine as a whole is simple and substantial in construction and requires very little power for its operation as all movements are transmitted through the crank 8 and cams 5. It, furthermore, prevents inequality of grinding and, therefore, insures a perfect finish in every instance.

15 The materials and finish of the several parts of the machine are such as the experience and judgment of the manufacturer may dictate.

I wish it understood that various changes 20 in form, proportions and details of construction may be resorted to within the scope of the appended claims and that I do not wish to limit myself to the specific design and construction here shown.

25 While I have shown and described the invention in its application to a grinding machine, the mechanical movement and principle involved is applicable to a variety of uses within the scope and purpose of the claims; 30 and the term "grinding machine" as used in the specification and claims simply indicates by way of illustration one practical use to which the invention has been specifically applied.

35 Having thus described my invention, what

I claim and desire to secure by Letters Patent is—

1. In a grinding machine, a casing, a spindle journaled in the casing, a disk secured on the spindle, a driving shaft journaled in the casing, a wheel having a plurality of angularly disposed cam members formed thereon, and projections on the disk engageable with the cam members.

2. In a grinding machine, a casing, a spindle journaled in the casing, a disk secured on the spindle, a driving shaft journaled in the casing, a wheel having a succession of cam members formed thereon of varying lengths, and roller pins on the disk with which the 50 cams are engageable.

3. In a valve grinding machine, a casing, a vertically disposed spindle journaled in the casing, a disk secured on the spindle, a plurality of upwardly extending roller pins 55 mounted on the disk, a cam wheel journaled in the casing at right angles to the disk, a plurality of elongated cam members formed on the wheel around its outer periphery engageable with the roller pins, said 60 cam members being of different lengths and disposed at angles opposite to each other, and means for rotating the cam wheel.

In testimony whereof I have hereunto set my hand in the presence of two subscribing 65 witnesses.

DANIEL W. HIGHTOWER.
